(57) CLAIM

The ornamental design for a fireplace, as shown and described.

DESCRIPTION

FIG. 1 is a top view of a fireplace, showing my new design; FIG. 2 is a front view thereof;

FIG. 3 is a side view thereof;

FIG. 4 is top view of a fireplace, shown in a different environment with a vertical stand;

FIG. 5 is a front view thereof;

FIG. 6 is a side view thereof;

FIG. 7 is a top view of a fireplace, shown in a different environment with a suspension rod;

FIG. 8 is a front view thereof;

FIG. 9 is a side view thereof;

FIG. 10 is a top view of a fireplace, shown in a different environment with a wall mount;

FIG. 11 is a front view thereof;

FIG. 12 is a side view thereof;

FIG. 13 is a bottom-up perspective view of FIG. 1; and,

FIG. 14 is a top-down perspective view of FIG. 1.

The broken lines shown in the drawings are for the purpose of illustrating portions of the fireplace that form no part of the claimed design.
